(57) **CLAIM**

The ornamental design for wall plate featuring embossed Sabbath candles, as shown and described.

DESCRIPTION

FIG. 1 is a perspective view of a wall plate featuring embossed Sabbath candles showing my new design;
FIG. 2 is a bottom plan view thereof;
FIG. 3 is a front view thereof;
FIG. 4 is a side view thereof, the opposite side being a mirror image thereof; and,
FIG. 5 is a top plan view thereof.
The broken line showing of a switch is included for the purpose of illustrating environmental structure only and forms no part of the claimed design.
